UNITED STATES PATENT OFFICE

134,835

DESIGN FOR A LICENSE PLATE FRAME

Vernon D. Griffith, Glendale, Calif.

Application September 22, 1941, Serial No. 103,440

Term of patent 7 years

To whom it may concern:

Be it known that I, Vernon D. Griffith, a citizen of the United States, residing in the city of Glendale, in the county of Los Angeles, State of California, have invented a new, original, and ornamental Design for a License Plate Frame, of which the following is a specification, reference being had to the accompanying drawing, forming a part thereof.

Figure 1 is a front elevational view of a license plate frame embodying my new design.

Figure 2 is a fragmentary enlarged elevational view of a portion 2—2 of the license plate frame shown in Figure 1.

Figure 3 is a fragmentary cross section taken on the line 3—3 of Figure 2.

Figure 4 is a fragmentary vertical cross section taken on the line 4—4 of Figure 2.

Figure 1 of the drawing is shaded to show contrasting color. The surface of the holder is a light reflector.

I claim:

The ornamental design for a license plate frame, as shown and described.

VERNON D. GRIFFITH.
